US0D1079678S

(12) **United States Design Patent** (10) **Patent No.:** **US D1,079,678 S**
(45) **Date of Patent:** **** Jun. 17, 2025**

(54) **EARPHONES**

(71) Applicant: **BELJING XIAOMI MOBILE SOFTWARE CO., LTD.**, Beijing (CN)

(72) Inventors: **Huacan Cui**, Beijing (CN); **Jiasheng Huang**, Beijing (CN)

(**) Term: **15 Years**

(21) Appl. No.: **35/520,053**

(22) Filed: **Feb. 10, 2023**

(80) **Hague Agreement Data**

Int. Filing Date: **Feb. 10, 2023**

Int. Reg. No.: **DM/227023**

Int. Reg. Date: **Feb. 10, 2023**

Int. Reg. Pub. Date: **Feb. 16, 2024**

(30) **Foreign Application Priority Data**

Aug. 16, 2022 (CN) 202230535823.X

(51) **LOC (15) Cl.** **14-01**

(52) **U.S. Cl.**

USPC **D14/223**

(58) **Field of Classification Search**

USPC ... D14/205, 207, 209.1, 217, 221, 223, 225;
D24/106, 173, 174; D29/112

Primary Examiner — Jack Reickel

Assistant Examiner — Russell Carnell Smith, Jr.

(57) **CLAIM**

The ornamental design for the earphones, as shown and described.

DESCRIPTION

2. Earphones

4. Earphones

2.1: Front View of First Component

2.2: Back View of First Component

2.3: Left View of First Component

2.4: Right View of First Component

2.5: Top View of First Component

2.6: Bottom View of First Component

2.7: First Perspective View of First Component

2.8: Second Perspective View of First Component

2.9: Front View of Second Component

2.10: Back View of Second Component

2.11: Left View of Second Component

2.12: Right View of Second Component

2.13: Top View of Second Component

2.14: Bottom View of Second Component

2.15: First Perspective View of Second Component

2.16: Second Perspective View of Second Component

4.1: Front View of First Component

4.2: Back View of First Component

4.3: Left View of First Component

4.4: Right View of First Component

4.5: Top View of First Component

4.6: Bottom View of First Component

4.7: First Perspective View of First Component

4.8: Second Perspective View of First Component

4.9: Front View of Second Component

4.10: Back View of Second Component

4.11: Left View of Second Component

4.12: Right View of Second Component

4.13: Top View of Second Component

(Continued)

4.14: Bottom View of Second Component

4.15: First Perspective View of Second Component

4.16: Second Perspective View of Second Component

The broken lines are for the purpose of illustrating portions of the earphones that form no part of the claimed design.

1 Claim, 32 Drawing Sheets
